John H. Calvert
ATTORNEY.

UNITED STATES PATENT OFFICE.

THOMAS GORDON, OF PHILADELPHIA, PENNSYLVANIA.

GAS-REGULATOR.

SPECIFICATION forming part of Letters Patent No. 461,829, dated October 27, 1891.

Application filed August 26, 1890. Serial No. 363,093. (No model.)

To all whom it may concern:

Be it known that I, THOMAS GORDON, a citizen of the United States, residing in the city of Philadelphia, State of Pennsylvania, have

5 invented certain new and useful Improvements in Gas-Regulators, of which the following is a full, clear, and exact description, reference being had to the accompanying drawings, forming a part of this specification.

10 My invention relates to gas or fluid governors applicable to regulating the flow of a current through the same to the supply-pipe of a lamp or other fixture, and has for its object the accomplishment of several purposes—viz., 15 the formation of the external supporting shell or frame of such shape and parts that while it may be secured at its inlet and outlet ends, respectively, to the inlet and exit supply-pipes, whether for ascending or descending 20 currents or for horizontal supply-pipes, all the working parts of the regulator may be removed for cleaning or repairs without loosening but a single joint—and also in the internal construction of the governor, where- 25 by the flow of gas is always downward upon the float, which is of such form as to constitute a passage-way in itself, is balanced by gas-pressure upon its lower surface, and is guided vertically by contact of its own de- 30 pending gas-tube against the inner case or shell, whereby a larger passage-way is secured, and consequently a greater capacity for any given size of regulator; and for these pur- 35 poses my invention consists, first, in the construction of the external shell or frame, and, secondly, of the internal working parts of the regulator, as hereinafter fully described.

In the accompanying drawings, illustrating 40 my invention, Figure 1 is a vertical sectional view of one form of my improved regulator, with the additional sketches above and below it, respectively, to show how it would be usually attached to a gas-lamp fixture. Fig. 2 is a like vertical sectional view of a modifica- 45 tion thereof in which the gas enters at the base of the regulator and has its exit at the top. Fig. 3 is also a vertical sectional view of another arrangement of the several parts in which the inlet and outlet are in the same 50 horizontal plane; and Fig. 4 is a vertical sectional view substantially similar to Fig. 1,

but without the additional supplemental arm, and intended to show more particularly the addition of the spring upon the periphery of the shell which contains the float.

55

In gas or fluid regulators of this class it has been the usual practice heretofore to construct a complete regulator and place it within a yoke or clamp, securing it therein by means of a movable flanged tube or collar, 60 said collar being in some cases made movable within the yoke and in other cases made movable upon the regulator and in most cases involving four or at least several joints, all of which require that care should be ex- 65 ercised to prevent leakage at the several joints. To overcome this objection is the object of the first part of my invention, the design of which is to construct the external shell of the regulator in such manner that it may be 70 fitted directly to the inlet and outlet supply-pipes without the intervention of any supporting-yoke and in such manner that it need not be afterward disturbed at either the inlet or outlet joints, while at the same time all 75 the working parts of the regulator may be removed for cleaning or repair and while it is in place upon the supply-pipes by the unscrewing of a single joint.

Referring to the drawings, Fig. 1, A below 80 the line *a a* is the external shell or case of the regulator, and *A'* is a supplemental arm terminating in an inlet-entrance *B*, said supplemental arm *A'* being hollowed out to form an inlet gas-passage *K*. An additional 85 supplemental arm *A*², similar to and opposite to the first, may be added for symmetry of construction, if desired; but it is by no means necessary. The open top of the external shell or casing *A* is closed by a screw-threaded 90 cap *A*², provided with an internal projection *D*', which when the cap is screwed down in place abuts against the periphery of the inner shell *T* to hold it in place in the external casing of the regulator. This shell is con- 95 structed in the shape of two hollow cylinders *T* and *G*, of different diameters, the former connected at its base to an intermediate annular plate *S*, which is provided with a central recess and an annular series of gas-aper- 100 tures *M*. The lower hollow cylinder *G* is fitted at its top within this central recess. Within

this inner shell is fitted loosely a float consisting of an annular plate I, circularly recessed at its center and having a depending hollow cylindrical tube J fitted thereto at its periphery in the central recess of the float-plate I. The closing-cap A² is so shaped either in the casting, as at H, Fig. 1, or by the addition of a screw, as at H, Figs. 2, 3, and 4, that it shall form a valve-seat with the top of the float, and thereby closing the entrance to the hollow depending tube J of the float. The design of this part of my invention is to avoid the use of the usual float-disk constructed with a central guide-rod or hollow post upon which the float moves vertically, as that form of float is objectionable in that the hollow central post occupies space which in my device is made available as a passage-way, by providing the float with a depending tube and guiding the latter externally by contact of its outer periphery with the interior of the inner shell, thus making the hollow depending tube of the float the exit gas-way of the regulator, by means of which construction a greater capacity is secured in any given size of regulator.

The essential features of the external shell of my improved regulator (shown in the several figures of the drawings) are a passage-way K² leading from the inlet-entrance B to a passage-way K', the communication between which two passage-ways is a valve-opening capable of being closed more or less by a regulating-screw F; also, another passage-way K, open at the top and leading also from said initial passage-way K², and a final passage-way A⁴, leading to the outlet C of the regulator. In case it is desired to attach my regulator to an ascending current instead of a descending or horizontal current it will be necessary to extend the outlet-passage A⁴ by means of a curved hollow arm A⁵, as shown in Fig. 2. Within this external shell A of the regulator is placed the internal shell T, S, and G, so arranged within the recess of the outer shell that it is capable of being lifted entirely out therefrom. The float also is in like manner capable of being lifted out of the inner shell in both cases without the use of tools. Within the said inner shell is fitted loosely the float I, with its depending tube J passing down into the cylindrical leg G of the inner shell. The central opening of this float forms a valve-seat with the projection H (see Fig. 1) of the cap A² or with the screw H (see Figs. 2, 3, and 4) of the cap A². In Fig. 4 is shown a spring D, which takes the place of the projection D' of Fig. 1 on the interior of the cap A² and serves to hold the inner shell or float-chamber in position. The parts being put together as described, the closing-cap A² is screwed in place on the outer shell. It is obvious from this description that when the regulator needs to be cleaned or repaired it will be unnecessary to remove it from its supply-pipes at B and C, but merely to unscrew the cap A² and lift out the inner shell

T S G, with the float I J, and after cleaning or repairing replace them in the manner described, and thus a single joint only need be opened for the purpose.

The operation of the device is as follows: The gas or other fluid enters at the inlet B and flows unrestricted through the passages K² and K, and thence through the perforations M in the horizontal annular plate S of the inner shell, there impinging upon the under surface of the disk I of the float. The pressure raises the disk I and its depending tube J until the mouth of the tube is brought into close proximity with the valve-seat formed upon the screw or projection H. If the depending tube J of the float is fitted to move gas-tight in the leg G of the inner shell and the passage-way K' is fully closed by the regulating-screw F, no gas will pass through the regulator. In some cases the float-cylinder may be quite loosely fitted; but when it is desired to have as wide a range of adjustment as may be possible at the valve of the adjusting-screw F it should be fitted as neatly as is compatible with the free movement of the float upon slight changes of pressure. When a volume of gas or fluid greater or less in amount is required, the passage K' is opened by a movement of the adjustment-screw F. A volume of gas is thus allowed to pass through the passage-way K' over the top of the inner shell and downward upon the top of the disk I of the float, which will have the effect to depress the disk I, allowing the gas to pass down through the depending tube I to passage-way A⁴ and through the outlet C of the regulator, and this depression of the disk will continue until an equilibrium is established between the pressures above and below said disk, after which the volume of fluid or gas delivered at the outlet C of the regulator will remain the same under all conditions of pressure at the inlet of the regulator in excess of the pressure required to overcome the inertia of the float.

Having thus described my invention, what I claim as new, and desire to secure by Letters Patent, is—

1. In a gas-regulator, the combination, with an external shell or casing open at the top and having an outlet-passage communicating directly with the open end of a hollow reciprocating gas-valve and a main inlet-passage divided into two inlet passage-ways by means of an adjustable regulating-screw, one of said inlets leading to a chamber in which said gas-valve is operated from below and the other of said inlets leading to a chamber in which said gas-valve is operated from above, of an inner shell forming a float-chamber and composed of two chambers of unequal diameter united by an intermediate annular plate provided with perforations communicating with the main inlet-passage, a reciprocating gas-valve consisting of an annular disk provided with a central hollow depending tube adapted to reciprocate within said inner shell or casing,

and a screw-cap or cover closing the top of said external shell or casing and provided on its inner surface with a valve projection adapted to close the port of the reciprocating valve when brought in contact therewith, said parts being constructed and combined substantially as set forth.

2. In a gas-regulator, the combination, with an external shell or casing provided with inlet and outlet passages and open at the top, of a removable cap adapted to close said opening, an inner shell or casing consisting of two open chambers of unequal diameter connected by an intermediate perforated annular plate and forming a float-chamber and partition between the inlet and outlet passages in the regulator, a reciprocating gas-valve consisting of a disk secured to a hollow spindle or tube, the latter forming a gas-passage communicating directly with the outlet-passage of the regulator, and an adjusting-screw acting as a valve to open more or less a passage-way leading from the inlet-chamber to the top of the inner shell or float-chamber, substantially as described.

3. In a regulator, the combination, with an external shell provided with main inlet and outlet passages and with an opening through which to insert and remove at pleasure the contained mechanism, of a removable cap adapted to close said opening, a removable inner shell or casing forming a float-chamber and partition between the inlet and outlet passages of the main casing, and a removable vertically-reciprocating valve operating therein, consisting of a disk and a tube, the latter leading directly downward from the inner casing or float-chamber to the main outlet-passage of the regulator, whereby said inner shell and its contained valve may be removed for cleaning, &c., by removing the said cap of the external shell and without disturbing or disconnecting the inlet and outlet connections to the regulator, substantially as described.

4. In a gas-regulator, the combination, with an external shell provided with inlet and outlet passage-ways and an open top, of a removable screw-cap A², adapted to close said top, an inner casing or shell constructed of two cylinders T G, of different diameters, with an intermediate annular plate S between them, and provided with gas-apertures M, a vertically-reciprocating gas-valve consisting of the disk I, with a depending cylindrical tube J communicating directly with the outlet passage-way of the regulator, and an adjusting-screw F, adapted to more or less divide the inlet-passage into two passages leading to the

top and bottom, respectively, of the reciprocating gas-valve, substantially as described.

5. In a gas-regulator, the combination, with an external shell open at the top and closed by a removable screw-cap, of a removable inner shell or float-chamber containing a reciprocating gas-valve provided with a central opening communicating directly with the outlet-passage-way of the regulator, said external shell or casing having an inlet-passage divided more or less by an adjusting-screw into two passages leading to the top and bottom, respectively, of said inner shell or float-chamber, substantially as described.

6. In a regulator, the combination, with an external shell or casing having a main inlet-passage and two other inlet-passages communicating therewith and leading to the top and bottom surfaces, respectively, of a reciprocating gas-valve, of external walls T G S, constructed as described and provided with gas-apertures M and forming a float-chamber and partition between the inlet and outlet passages of the main shell or casing, and a reciprocating gas-valve consisting of the disk I, provided with a central depending tube J, adapted to move and be guided within said internal wall G by contact of its exterior surfaces therewith, said reciprocating valve forming the sole means of exit to the outlet-passage of the regulator, substantially as described.

7. In a gas-regulator, and in combination with an external shell having a main inlet-passage K² and a second passage K', an inner shell or casing constructed as described and forming a float-chamber and a partition between the inlet and outlet passages of the main casing, a reciprocating gas-valve consisting of an annular disk and depending cylinder moving vertically in said inner casing and having a central opening through which the gas may flow in a downward direction, and an adjusting-screw F, adapted to more or less restrict the flow of gas to said passage-way K', whereby an unrestricted flow of gas is delivered to the lower surface of said reciprocating valve, while a restricted and adjustable volume thereof is delivered to the upper surface of said valve, substantially as described.

In testimony whereof I have hereunto affixed my signature this 31st day of July, A. D. 1890.

THOMAS GORDON.
